(57) **CLAIM**

The ornamental design for a corrugated wipe dispenser, as shown and described.

DESCRIPTION

FIG. 1 is a front perspective view of a corrugated wipe dispenser showing my new design, according to a first embodiment, in a first position;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and

FIG. 7 is a bottom plan view thereof.

FIG. 8 is a front perspective view of a corrugated wipe dispenser showing my new design, according to a first embodiment, in a second position;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and

FIG. 14 is a bottom plan view thereof.

FIG. 15 is a front perspective view of a corrugated wipe dispenser showing my new design, according to a second embodiment, in the first position;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof; and,

FIG. 21 is a bottom plan view thereof.

The evenly-spaced dashed broken lines in the figures depict portions of the box that form no part of the claimed design. The dot-dash broken lines in the drawings represent the bounds of the claim and form no part of the claimed design.

1 Claim, 21 Drawing Sheets
